UNITED STATES PATENT OFFICE

2,419,861

NEEDLE THREADER

Frank Vogel, Philadelphia, Pa.

Application May 4, 1945, Serial No. 591,947

2 Claims. (Cl. 223—99)

1

The present invention relates to needle threading devices, the threading of needles used in hand sewing, and the object of the invention is to devise simple means for quickly and easily passing a thread through the eye of a needle, without hesitation on the part of the operator thereby eliminating waste of time.

Another object is to provide means to attach the device to the spool upon which the thread is wound, providing a handle and also a stand. Other objects and advantages will be apparent as the nature of the invention is understood.

The invention is characterized by simplicity of construction, inexpensiveness of manufacture and practicability in use.

Referring to the drawings in which similar reference characters designate corresponding parts:

Figure 1 is a front elevation of the needle threading device.

Figure 2 is a side elevation of the needle threading device.

Figure 3 is a top plan view of the same device.

Figure 4 is a side elevation showing a modified form of the needle threading device.

Referring to the illustrations, 1 indicates the body, which is preferably made from a blank, bent double in U-shape forming a double spaced body, the front elevation resembling a letter Y.

A narrow arm 2 and wide arms 3 and 4 are extending upwardly and angularly from body 1, narrow arm 2 being bent in U-shape forming a needle guiding channel and wide arms 3 and 4 comprising a double spaced arm having a springy tension against each other, facilitating the guiding and aligning the needle in center of the body.

As shown in the illustrations, the narrow arm 2 and wide arm 3 are flanged and bent outwardly at the top ends to accommodate the needle more conveniently, at the start of the needle threading operation. Between the narrow arm 2 and wide arms 3 and 4 a V-shaped recess 5 is cut away, terminating in narrow slots 6 and these said slots are cut in both sides of the body to a fair depth ending at 7, to provide additional flexibility to wide arms 3 and 4.

At the root of the recess 5 and at the beginning of slots 6 and in between body 1 is located the thread engaging hook 8. This said hook is preferably made of a thin and tough material and is composed of the hook 8 itself and its depending body 9. A short distance below the hook 8 a wider shoulder 10 is formed to stop the needle at the required depth. The rivet 11 holds the

hook and body 9 in between body 1 securely in place.

At one side of body 1 and approximately level with the shoulder 10 a depending strip of material is being bent at right angles and transversely, forming a heel 12 to provide another stop to keep the needle at the proper level at the bottom stroke. Wide arm 4 is bent to right angles at 13 and a short distance away bent upwardly and over upon itself forming a U-shaped spring clip 14. At the outer edges of this spring clip 14 an inwardly tapered needle receiving mouth 15 is formulated and a pair of parallel running ribs 16 and 17 are formed across the flat of the material and angularly as shown at 18 to guide the needle in the center of the device.

The lower portion of body 1 is cut to a taper as shown in Fig. 1 to enable a person to force the needle threading device into the bore of 20 the thread spool to have a convenient stand for the device.

Furthermore, the hole 19 at the lower end is also accommodating the user to either attach it to a string or place it on a nail.

25 In Fig. 1, Fig. 2 and Fig. 3 the threading device is shown with the thread 20 and needle 21 in position before retracting the needle upwardly. As is shown in Fig. 2 the arms 3 and 4 are spread out when the needle is placed between them, due 30 to the flexibility the said arms possess, which is necessary to accommodate various needle sizes.

To explain the use of the threading device, the operator places the eye end of the needle into mouth 15 and forces it toward narrow arm 2 and 35 as the needle proceeds deeper due to the springy tension of the spring clip 14, the eye of the needle is forced to turn flatwise, aligning the needle correctly. As the needle proceeds further it is forced against the side of angularly running rib 17 which 40 will guide the needle in the center of the device and into the channel portion of the narrow arm 2. When this stage is reached the needle is pressed downward guided by the channel of the narrow arm 2 and the wide arms 3 and 4 the 45 hook 8 will pass through the eye of the needle and the needle will come to a stop account of shoulder 10 and heel 12 and held there by the tension of wide arms 3 and 4. When in this position a thread 21 is placed by the operator transversely in the V-shaped recess 5, pressing it 50 downwardly, the thread will reach the hook 8 and since the said hook is aligned between narrow slots 6 in such a way that a downward angle is formed by hook 8 and the extreme point at 22 55 on hook 8 projects beyond the edges of narrow

slots 6 thereby the thread 21 will snap in and under hook 8, holding it there indefinitely. After having the needle and the thread in this position the operator retracts the needle upwardly, the thread engaged by the hook member is drawn through the eye of the needle, thereby completing the threading operation.

It should be understood that it is not necessary to use the needle registering spring clip 14 to align the eye of the needle, if the operator is willing and able to position the eye correctly, then the needle can be placed directly in the channel 2 and between arms 3 and 4 and carry through the operation as described.

For this purpose a slightly modified device is shown in Fig. 4. This threading device is substantially the same as shown in Fig. 1, Fig. 2 and Fig. 3, only the needle registering spring clip 14 is eliminated and both the top ends of wide arms 3 and 4 are bent outwardly to accommodate the needle. In Fig. 4 the needle 20 and thread 21 are not shown.

It is understood, that various changes in the form, proportion and minor details of construction may be resorted to without departing from the spirit of the invention.

What is claimed is:

1. In a needle threader of the class described, a spaced double body, narrow and wide arms extending upwardly and angularly from said body, said arms constituting a needle guiding channel and clip respectively, a thread receiving and guiding recess terminating in narrow slots, a thread and needle engaging hook in between said body, said hook aligned in between said narrow slots, and functioning to releasably hold the thread between edges of said narrow slots, needle depth stops on said hook member and said body, one end of said wide arms being bent at right angles thereto, and then upwardly and over upon 40

itself forming a spring clip, the outer edges of said spring clip being formulated into an inwardly tapered needle receiving mouth, said mouth terminating into a needle guiding rib angularly disposed across the flat of said spring clip, and the lower stem of said body being tapered to fit the bore of a spool.

2. A needle threader comprising a spaced double walled relatively flat body forming a needle receiving channel between said walls, narrow and wide arms extending upwardly and angularly from said body, the space between the sets of arms forming a thread receiving and guiding recess terminating in narrow slots, a thread and needle engaging hook fixed between the walls of the body and aligned between said narrow slots whereby edges of the latter guide thread into engagement with the beak of said hook, and a spring clip formed as an integral part of the upper end of one of said wide arms and projecting outwardly laterally relative thereto, said spring clip comprising substantially parallel spaced walls with oppositely curved tapered portions cooperating to produce a needle receiving mouth terminating in a needle guiding rib leading to the needle receiving channel.
